CLAIM

The ornamental design for a decorative planter, as shown.

DESCRIPTION

FIG. 1 is a top, front and left-side perspective view of a decorative planter incorporating our design; FIG. 2 is an enlarged, front elevational view thereof; FIG. 3 is an enlarged, right-side elevational view thereof, the left-side elevational view being a mirror image;

FIG. 4 is an enlarged top plan view thereof;

FIG. 5 is an enlarged rear elevational view thereof;

FIG. 6 is a bottom view thereof; and,

FIG. 7 is a sectional view thereof taken along line VII—VII of FIG. 4.
